JAMES DAVID MACDONALD, OF MOSMAN, NEAR SYDNEY, NEW SOUTH WALES,
AUSTRALIA

LACE-FASTENING MEANS FOR FOOTWEAR

Application filed January 25, 1929, Serial No. 335,067, and in Australia May 31, 1928.

This invention relates to shoe and boot laces constructed of elastic cord or elastic tape, and it consists in adjustable tautening and holding means associated with such laces for terminally securing them when they are reeved taut in the eyelets, in such a way that slipping is effectively prevented and so that the fastening devices and the lace ends will be entirely secreted and discomfort to the wearer obviated.

The complete fastening comprises a length of braided elastic cord or tape of appropriate dimensions, carrying stoppers which are adapted structurally to lie flatwise between the eyeleted flaps and the tongue of the shoe; one or both stoppers is or are slideable along the cord or tape but only in the direction of shortening the distance between the stoppers. The movable stopper (or stoppers) is a metal plate having a hole through it with the metal at the rim of the hole slotted and upset to form barbs. There is sufficient clearance in the hole to allow the elastic lace to be drawn through the hole in one direction, but insufficient clearance is offered to allow the lace to be drawn through the hole in the opposite direction as the barbs on the stopper engage it to the lace and so lock it when an attempt is made to move the stopper in the reverse direction along the lace so that the distance between the two stoppers would be increased. When only one movable stopper is used, a permanent stopper is fixed on one end of the lace.

In the accompanying drawing:—

Fig. 1 is a perspective side view of a shoe in process of being laced;

Fig. 2 is a fragmentary frontal perspective view showing the shoe and the lacing as they appear when the reeved-in lace has been through the eyelets in the shoe flanks;

Fig. 3 is a fragmentary frontal perspective view showing the shoe and the lacing as they appear when the reeved-in lace has been drawn taut and fixed by the stopper which is carried on the upper end of the lace;

Fig. 4 is a perspective view of a length of tape pattern braided elastic lace carrying two one-way slideable stoppers;

Fig. 5 is a perspective view of one of the stoppers;

Fig. 6 is a fragmentary perspective view of a short length of lace having a permanent stopper fixed on it; and

Fig. 7 is a transverse section on the line 7—7, Fig. 6.

The stopper Fig. 5, is a disc 10 of hard metal one-half inch more or less in diameter, with cross slotted incisions in the center of it leaving a cruciform aperture 11 with tangs 12 upset in the same direction, forming barbs, which are adapted to engage the braided lace 13 in the manner indicated in Fig. 4. These stoppers are slideable along the lace inwardly from the ends thereof on which they are respectively entered, but they are immovable in the opposite direction, as the barbs engage the lace and check movement of the stoppers.

Any form of stopper may be used on the lower end of the lace, either the type of stopper shown in Fig. 5 or the type shown in Figs. 6 and 7, or otherwise, so long as it is such that it will nest flat between the last eyelet hole in the flank flap 14 and the underlying part of the shoe upper just above the root of the tongue 15. The stopper which is provided on the upper end of the lace must, however, be a one-way running stopper such as shown in Fig. 5.

In lacing a shoe or boot, a stopper as hereinbefore described is fixed on the lower end of the lace, and the lace is then reeved successively through the pairs of eyelets in the respective flaps, crosswise, as seen in Figs. 2 and 3, commencing under the lowest eyelet on one flap and finishing under the highest eyelet on the other flap. The lace is then drawn taut as suggested in Fig. 3, and a one-way barbed stopper Fig. 5 is slipped over the end of it and pushed down along it until it comes tightly up under the top eyelet through which the last downward pass of the lace has been made. The spare length of the lace above the stopper is then cut off. The lace is thus permanently fixed and holds the two flaps drawn tightly up to abutting position as seen in Fig. 3. The elasticity of the lace allows of the neck of the shoe being sprung open sufficiently to permit of the shoe

being put on and taken off the foot, and it operates to close and hold the flaps in the closed position whilst the shoe is being worn and whilst it is out of use. The lace may stretch and elongate more or less in prolonged use. The surplus length may be taken up from time to time by forcing the top end stopper further along the lace, the released waste end being then cut off.

10 A fixed stopper for the lower end of the lace is illustrated in Figs. 6 and 7. It consists of a flat metal tube 20 through which the end of the lace 21 is reeved; the sides of the stopper are compressed inward (22) to pinch it on the lace 21 and thus to secure it permanently thereon. In the drawing, the thickness of the tube is exaggerated for better illustration. These stoppers should be no thicker than is necessary for their integrity as it is required that they will not form a protrusion in the shoe which would cause discomfort to the foot of the wearer or mar the external appearance of the shoe. It is not necessary that either stopper be of disc shape, but it is preferred that they be of disc or oval shape on account of its obvious convenience.

What I claim as my invention and desire to secure by Letters Patent is:—

30 A one way slideable stopper for an elastic shoe lace, consisting of a hard metal plate slit in the shape of a cross to form an aperture and the portions adjacent the slit being upset to form barbs which surround the aperture and permit the lace to be drawn through the aperture in one direction only.

In testimony whereof I affix my signature.
JAMES DAVID MACDONALD.
